UNITED STATES PATENT OFFICE.

EDWIN C. CHARLES, OF OIL CITY, PENNSYLVANIA.

SPARK PLUG.

Application filed March 13, 1923. Serial No. 624,807.

To all whom it may concern:

Be it known that I, EDWIN C. CHARLES, a citizen of the United States, residing at Oil City, in the county of Venango and State 5 of Pennsylvania, have invented new and useful Improvements in Spark Plugs, of which the following is a specification.

This invention relates to pumps, and more particularly to what I term a spark plug 10 compression pump.

One of the main objects of the invention is to provide a pump of simple construction and operation which may be readily applied to the spark plug of an internal combustion engine for the purpose of utilizing one cylinder and piston of the engine as an air compressor or pump for inflating tires and other purposes. A further object is to provide a pump of the character described 15 of simple construction and operation which may be used in connection with a spark plug similar to a standard type of spark plug. A further object is to provide simple and efficient means for detachably securing the 20 pump in operative position. Further objects will appear from the detailed description.

In the drawings:

Figure 1 is a central vertical section 30 through the spark plug adapted for use in connection with the pump;

Figure 2 is a top plan view of the spark plug;

Figure 3 is a top plan view of the pump;

Figure 4 is a section taken substantially 35 on line 4—4 of Fig. 3;

Figure 5 is an end view of the pump.

To permit the pump to be readily applied I use a spark plug such as that illustrated in 40 Figures 1 and 2. This plug includes a body 1 having a depending neck 2 adapted to be threaded into the usual opening provided in cylinder A of the engine, this neck being provided with a terminal element 3. A head 4 fits into the upper portion of body 1 which is provided with an enlarged bore for this purpose, this head being provided with a reduced collar 5 which fits into body 1 so as to provide a shoulder between which and a 45 corresponding shoulder in the body is positioned a packing gasket 6. A porcelain body 7 is mounted in head 4 and is secured in position by a ring 8 threaded into the upper end of the head, this body being provided 50 with a screw stem 9 for reception of the usual nuts for attaching a terminal ele-

ment of an electrical circuit. A contact rod 10 extends from stem 9 and is spaced, at its lower end, from contact element 3 to provide a spark gap, which is made correct by the 60 index stud 12^a with its large diameter portion. Body 1 is provided with outwardly projecting lugs 11 in which are secured studs 12 and 12^a which pass through openings provided through lugs 13 projecting from head 65 4. Nuts 14 are threaded on the upper ends of studs 12 and 12^a and bear upon lugs 13 so as to hold the head 4 tightly seated in body 1. In practice one cylinder of the 70 engine is provided with a spark plug of the character illustrated and described.

When it is desired to utilize the pump nuts 14 are removed thus permitting ready removal of head 4 and the parts carried thereby, after which this head is replaced 75 by the pump. The pump includes a casing 15 from one end of which extends an intake tube 16. A spider 17 is threaded in the outer end of this tube and carries, at its inner end, a disc 18 between which and a disc 19 is secured an inwardly directed cup washer 20 of leather or other suitable material. Tube 16 communicates, at its inner end, with tubular body 21 of casing 15 through an intake opening 22. A spider 23 80 is secured in the upper portion of body 21, which is slightly reduced in interior diameter, and an outwardly directed cup valve 24 is secured on the upper end of stem 23^a carried by this spider. Valve 24 fits within 85 a tubular plug 25 threaded into the upper end of casing 15, and a packing gasket 26 is confined between the lower end of this plug and a shoulder 27 provided at the upper end of body 21. At its upper end plug 25 is 90 provided with a nipple 28 adapted for reception of a length of rubber tubing or hose 29 by means of which the outlet of the pump 95 can be readily connected to a tire or other object to be inflated. The lower portion 21^a 100 of body 21 is adapted to fit into the upper portion of body 1 of the spark plug and is secured tightly in position by means of studs 12 and 12^a and nuts 14, the casing 15 being provided with outwardly projecting lugs 30 105 for reception of the studs. This provides simple and efficient means whereby the pump may be readily applied and, during operation of the engine, on the suction stroke of the piston air is drawn into the cylinder 110 through intake tube 16 and on the compression stroke of the piston this air is forced

through nipple 28 into tube 29 and thence into the tire or other object to be inflated. This provides very simple and efficient means whereby the engine may be utilized 5 as a pump for inflating tires or other objects.

I provide a pressure regulating valve from body 21 which has graduations on part 36 and permits the operator to set 10 the pump for any pressure required to be inflated. At the opposite end of casing 15 from intake tube 16 I provide a pressure regulating valve tube 31 which communicates with the bore of body 21 by an opening 32 in the outer end of which is normally seated a valve 33 of frusto-conical shape. This valve is provided with an outwardly projecting hollow cylindrical body 34 within which seats one end of a compression coil spring 35 the other end of which is seated in a hollow plug 36 threaded into the outer end of tube 31. This plug is provided with an outlet bore 37 communicating at its inner end with the recess which 25 receives the outer end of spring 35. By adjusting plug 36 the pressure at which the valve 33 will be unseated can be regulated to suit requirements. When the air pressure within body 21 of the pump casing 15 reaches the predetermined pressure valve 33 is unseated permitting the air to escape through opening 32 into tube 31, this air being discharged through bore 37 30 of plug 36 into the atmosphere.

25 While I have illustrated and described

cup valves as used in the pump, I can, if preferred, use any other well known type of valve such as ball valves, disc valves, ground seated valves, or any other suitable or preferred type of valves, as will be understood. As above indicated, changes in details of construction and arrangement of parts of the invention may be resorted to without departing from the field and scope of the same, and I intend to include all such 40 variations, as fall within the scope of the appended claims, in this application in which a preferred form only of my invention is disclosed.

What I claim is:—

In a spark plug, a body having a neck adapted to be secured in an opening in an internal combustion engine cylinder, a head fitting into said body, a second body carried by said head, a terminal member carried by said second body, a terminal member carried by the first mentioned body, studs carried by said first mentioned body, said studs being differently shaped, the head being provided with lugs having openings to receive the respective studs for positioning the head in predetermined relation to the first mentioned body, and means coacting with said studs for detachably securing the head and the first mentioned body 60 together.

In testimony whereof I affix my signature.

EDWIN C. CHARLES.
